UNITED STATES PATENT OFFICE.

VICTOR C. BALDING, OF LITTLE ROCK, ARKANSAS.

TELEGRAPH APPARATUS.

No. 856,837.

Specification of Letters Patent.

Patented June 11, 1907.

Application filed March 12, 1906. Serial No. 305,614.

To all whom it may concern:

Be it known that I, VICTOR C. BALDING, a citizen of the United States, residing at Little Rock, in the county of Pulaski and State of Arkansas, have invented certain new and useful Improvements in Telegraph Apparatuses; and I do declare the following to be a full, clear, and exact description of the invention, such as will enable others skilled in the art to which it appertains to make and use the same.

This invention relates to improvements in instructing devices for telegraph operators.

The object of the invention is to provide a device of this character by means of which the movement of the contact lever of a sounder may be recorded upon a tape or ribbon in such a manner that said record may be transmitted to another sounder.

With the above and other objects in view, the invention consists of certain novel features of construction, combination and arrangement of parts, as will be hereinafter described and claimed.

In the accompanying drawings:—Figure 1 is a plan view of the recording mechanism of the apparatus; Fig. 2 is a side view of the same; Fig. 3 is a front end view of the recording sounders; Fig. 4 is a detail sectional view through a portion of the tape guide, showing the manner of adjusting the same; Fig. 5 is a vertical sectional view through the tape reel, showing the same connected with the motor; and Fig. 6 is a cross sectional view through the motor shaft, showing the reel in side elevation.

Referring more particularly to the drawings, 1 denotes the recording instrument of the apparatus, said instrument comprising a telegraph key 2 and a sounder 3 connected therewith, said key and sounder being arranged in a suitable electric circuit. The key 2 is of the usual or any suitable construction provided with the usual switch 4. The sounder is here shown and is preferably of a double construction, that is, consisting of two electro-magnets 5, each of which is provided with the usual armatures 6 and contact levers 7. To one end of the contact lever 7 and connecting the same is secured a supporting frame 8, said frame consisting of suitably mounted cross bars 9 and an upwardly projecting yoke-shaped brace 10.

In the supporting frame 8 is secured a tape perforating instrument, said instrument being here shown and is preferably in the form

of a pyrographic burning point 12 connected with a pyrographic apparatus of any suitable construction by means of which the point 12 may be kept heated to the necessary degree for burning perforations in the tape when the same is drawn beneath said point. The pyrographic outfit is shown in the present instance as of the ordinary benzene vapor-generating type, having an elastic pressure bulb for forcing vapor to the point.

Arranged between the electro-magnets of the sounder and below the point 12 is a tape guide 13, said guide being here shown as a longitudinally disposed bar or plate having upwardly projecting side flanges 14, which form a channel through which the tape is adapted to be drawn. To the flanges 14 are connected spring fingers 14' which are adapted to hold the tape down in sliding engagement with the guide bar 13. In the forward end of the bottom plate of the guide is formed an aperture 15 sufficiently large to permit the guide to be adjusted without danger of the end of the point coming into contact therewith. The opposite ends of the guide bar 13 are bent downwardly and outwardly as shown at 16, and in said outwardly bent ends is formed an aperture, through which is arranged an upwardly projecting threaded bolt 17. On the bolt 17 above and below the end of the guide bar are screwed adjusting nuts 18 which may be screwed in one direction or the other to adjust the height of the guide plate or bar. The holes through which the bolts 17 pass are sufficiently large to permit the guide bar to be shifted laterally or longitudinally. After the bars have been adjusted and raised to the desired position, the nuts are tightened up to hold the same in said adjusted position.

In order that the tape 19 may be properly fed to the guide 13, said tape is preferably wound upon a suitably mounted reel 20 arranged at the rear end of the sounder, as shown. At the opposite end of the sounder is arranged a winding reel 21, upon which the perforated tape is adapted to be wound. The reel 21 is preferably mounted upon the drive shaft 22 of a motor 23. The reel 21 preferably consists of a winding drum 24 having on its inner edge oppositely disposed radially projecting guide fingers which guide and retain the tape upon the periphery of said drum. The drum 24 is provided with a hub portion 25, through which the end of the

drive shaft 22 is passed, thus loosely mounting the reel upon said shaft. On the outer end of the shaft 22 is arranged a disk or head 26 against which the outer side of the hub 25 is adapted to bear. On the shaft 22 is also fixed a stop collar 27, and between said collar and the adjacent side of the drum 24 is arranged radially projecting springs 28 which are adapted to bear on said drum and to force the end of the hub 25 into frictional engagement with the disk 26, thereby yieldingly connecting said drum with the shaft. The pressure of the springs 28 is such that the reel will be held sufficiently tight to permit the same to draw the tape through the guide bar of the recording instrument from the reel 20. The connection of the reel 21 with the drive shaft of the motor is not sufficiently tight however to prevent a retrograde movement of said reel in unwinding the tape therefrom.

The motor 23 may be of any suitable character, the same being here shown and is preferably in the form of a weight motor, by means of which a uniform movement will at all times be imparted to the winding reel; the motor will be provided with a suitable governing device (not shown).

The recording instrument may be operated in connection with a suitable transmitting device, by means of which the characters formed in the tape by said recording instrument may be transmitted to another sounder or series of sounders, for the purpose of instructing students in telegraphy.

By means of a telegraph apparatus constructed and arranged as herein shown and described, all branches of telegraphy such as commercial, rail-road, associated press, race track, etc. may be readily taught.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as defined by the appended claims.

Having thus described my invention, what I claim as new and desire to secure by Letters-Patent, is:—

55. 1. In apparatus of the class described, in combination with a perforator and means to move a tape longitudinally and present the same to the action of the perforator, a tape guide comprising a plate having side flanges forming a channel for the tape, spring devices to hold the tape against the plate and between the flanges, and means to support and vertically adjust said guide, substantially as described.

60. 2. In a telegraph apparatus of the char-

acter described, the combination with a key and sounder, said sounder comprising two electro-magnets each having armatures and contact levers, of a supporting frame connected to and operated by said levers, a perforating instrument carried by said frame, a tape guide arranged beneath said instrument, means to adjust and hold said guide in position, and means to draw a tape through said guide, substantially as described. 75

3. In a telegraph apparatus of the character described, the combination with a key and sounder, said sounder comprising two electro-magnets each having armatures and contact levers, of a supporting frame connected to and operated by said levers, a perforating instrument carried by said frame, a tape guide arranged beneath said instrument, supporting bolts arranged at the ends of and adapted to pass through said guide, adjusting and holding nuts arranged on said bolts above and below the ends of said guide, and means to draw the tape through said guide, substantially as described. 80

4. In a telegraph apparatus of the character described, the combination with a key and sounder, said sounder comprising two electro-magnets each having armatures and contact levers, of a supporting frame connected to and operated by said levers, a perforating instrument carried by said frame, a tape guide arranged beneath said instrument, supporting bolts arranged at the ends of and adapted to pass through enlarged apertures in said ends of the guide, adjusting and securing nuts arranged on said bolts above and below said ends of the guide, a reel to contain imperforated tape, a winding reel to receive the tape after being perforated, and means to operate said reel, thereby causing 100 the same to draw the tape through said guide and to wind said tape upon itself, substantially as described. 105

5. In a telegraph apparatus of the character described, the combination with a key and sounder, said sounder comprising two electro-magnets each having armatures and contact levers, of a supporting frame connected to and operated by said levers, a perforating instrument carried by said frame, a 110 tape guide arranged beneath said instrument, supporting bolts arranged at the ends of and adapted to pass through enlarged apertures in said ends of the guide, adjusting and securing nuts arranged on said bolts above and below said ends of the guide, a reel to contain imperforated tape, a winding reel to receive the tape after being perforated, a weight motor, and means to frictionally engage said winding reel with the drive shaft of said motor, substantially as described. 115

6. In a telegraph apparatus of the character described, the combination with a key and sounder, said sounder comprising two electro-magnets, each having armatures and 120

130

contact levers, of a supporting frame connected to and operated by said levers, a pyrographic device having its burning point secured in and operated by said supporting frame, an apertured tape guide arranged beneath said frame and point, means to adjust and hold said tape guide in position, a reel to contain imperforated tape, a winding reel to receive the tape after being perforated by

5

10 said pyrographic point, a weight motor having a drive shaft to receive said winding reel,

and springs to hold said reel in frictional engagement with said shaft, substantially as described.

In testimony whereof I have hereunto set 15 my hand in presence of two subscribing witnesses.

VICTOR C. BALDING.
